Primary Examiner — Elizabeth Albert(74) *Attorney, Agent, or Firm* — Calfee, Halter & Griswold LLP(57) **CLAIM**

I claim the ornamental design for a file folder, as shown and described.

DESCRIPTION

FIG. 1 is a top plan view of a first embodiment of the file folder, shown in FIG. 1 in an open orientation;
FIG. 2 is a front elevational view thereof;

The broken lines that are extensions of solid lines (where the solid lines transition to become the broken lines) and the broken lines adjacent the margins of the pages represent the bounds of the claimed design, while all other broken lines are

directed to environment and are for illustrative purposes only; the broken lines form no part of the claimed design.
